Patented Aug. 30, 1927.

UNITED STATES PATENT OFFICE.

ALWIN G. STEINMAYER, OF MILWAUKEE, WISCONSIN, ASSIGNOR TO LINE MATERIAL COMPANY, OF SOUTH MILWAUKEE, WISCONSIN, A CORPORATION OF WISCONSIN.

SAFETY PULLEY.

Application filed February 15, 1926. Serial No. 88,467.

This invention relates to certain new and useful improvements in safety pulleys employed in connection with street lighting fixtures, more particularly that type known in the art as the two-way and four-way holophane refractor.

Heretofore the safety or one-way pulleys for the suspension of street lighting fixtures have not been used in connection with the two and four-way refractors, in that the safety pulleys now in use allow the refractor or fixture to rotate. It is of prime importance that a refractor of the two or four-way type be restrained against rotation while suspended and that it be returned to its proper position each time. Therefore, it is an object of this invention to provide a safety pulley having means for returning the fixture to its proper position with respect to the roadway after each operation.

Another object of this invention resides in the provision of a safety pulley having means cooperating with the fixture for aligning the same in a predetermined relation with the pulley upon engagement of its carrying means therewith.

A further object of this invention resides in the provision of a suspension means of the class described consisting of a stationary and a movable part having cooperating means for aligning a fixture carried by the movable part in a predetermined relation with the fixed part during the engagement of the stationary part therewith and restraining the same against rotation after its engagement with the stationary part.

And a still further object of this invention resides in the provision of a device of the character described which is positive in its action, of simple construction and has ample protection against the elements.

Figure 1 is a perspective view of a street or roadway intersection equipped with a lighting fixture having a four-way holophane refractor, said view diagrammatically illustrating the directional qualities of the light rays;

Figure 2 is a view in side elevation of a safety pulley and fixture embodying my invention, parts thereof being in section to more clearly illustrate constructional details thereof, and

Figure 3 is a cross sectional view taken on the plane of the line 3-3 of Figure 2.

Referring now more particularly to the

accompanying drawings, in which like numerals designate like parts throughout the several views, the numeral 5 designates a street or roadway intersection at diagonal corners of which two poles 6 and 7 are mounted. The pole 7 may support the usual line wires, one of which forms the supply line for the lighting fixture 8 suspended from the center span wire 9 connecting the poles substantially as shown and the arrows 10 illustrate the direction of the concentrated rays of a fixture of this type.

A pulley block housing 11 is suspended from the span wire 9 by a clamping member 12 which has its channel (not shown) through which the wire passes, curved to guard against creeping of the member 12 therealong.

The housing 11 forms substantially an enclosure being open only at its bottom and having a small opening at the top to allow an operating cable or rope 13 to be passed through. The housing comprises two complementary side walls 14, between which a pulley 15 is journaled, as at 16, at its upper end portion, and two end walls 14', one of which terminates short of the other to incline the housing bottom as illustrated.

The fixture 8 has a threaded bore 17 in its top surface into which the threaded stud 17' of a tubular rope securing member 18 is secured, the bore of said member terminating in an annular channel or recess formed in an enlarged portion 18' having its outer wall notched, as at 19. The rope 13 has one end passed through the bore of member 18, around in the annular channel of the enlargement 18' and out of the groove or opening 19, being anchored at this point by a flange member 20 drawn down tight by a nut 21 threaded onto a screw 21. The other end of the rope is brought up through the elongated opening in the bottom of the housing over the pulley, out through the small opening at the top of the housing, over a pulley 22 secured to pole 6 and then down along the pole to be removably secured thereto, as at 23.

The upper end of the member 16 has a knob 24 formed thereon which cooperates with guides 25 formed on the inner surfaces of the housing side walls. The walls 13 are spaced a distance substantially equal to the diameter of the knob whereas the distance between the opposite guides 25 is less, being substantially equal to the diameter of the

member 16. The guides 25 are so arranged as to form an entrance 26, an approximately V-shaped rest 27, an exit 28 and passage-ways 29 and 30 connecting the same. In the 5 normal or operative position of the fixture, the knob 24 is supported by the rest 27 and when it is desired to lower the fixture, the rope is drawn up causing the knob to travel up through the passageway 29 and into the 10 passage-way 30. Releasing the tension on the rope allows the knob to pass through the passage-way 30 and out through the exit 28.

In returning the fixture to its operative 15 position, the rope is drawn up until the knob contacts with the guides 25 on the lower or bottom portion of the housing and defining one side of the rest 27 and travels therealong until it reaches the entrance 26 20 and swings thereinto. The tension on the rope is then released and the knob moves into the rest 27.

The point of suspension of the housing 11 is so placed with respect to the distributed 25 weight thereof that it hangs by gravity in a position with the entrance 26 to one side and the throat of passage 30 and exit 28 on the other side of the true plumb axis of the rope 13.

30 In entering, the member 18 is swung to one side of its true vertical position by engagement of the knob with the lower, outer guides 25 until the knob 24 reaches the entrance 26 where it is free to swing by gravity into its true vertical position, at which point it is aligned with the passage into the rest 27. Releasing the tension of the rope allows the knob to seat itself on the rest 27 and secure the fixture in operative position.

35 As above described, to lower the fixture, tension is applied to the rope whereupon the knob 24 enters the throat of passage-way 29, the entrance to which is in line with the true vertical axis of the rope and continued upward movement of the knob causes the member 18 to ride to one side of its plumb axis until it reaches the throat of passage 30. Here again member 18 is free to swing back into its plumb position registering with 40 the entrance to the passage 30 and when the tension on the rope is released the knob is guided down through the passage 30 and out the exit 28. The exit 28 is offset a relatively 45 large distance with respect to the true plumb 50 of the fixture to guard against any possibility of the knob entering at the exit.

In order to insure that the rays of light be always in the same direction, it is necessary that the knob enter the housing always in the same manner. To accomplish this, the upper end of the member 16 is provided with a laterally projected boss 31 of the same thickness as the diameter of the barrel of member 16, thereby enabling the boss to pass between the opposite guides 25, but restraining all rotation of the member 16. It will be obvious that this projection serves as a simple means for insuring the return of the fixture to its proper position with the light rays in the desired directions, and does not in any way affect the operation of the knob. 60 65 70

Besides the position in which the fixture is shown in Figure 2 of the drawings, it is possible that it be twisted 180 degrees, and 75 enters the housing in that manner. This is not objectionable as it will in no way affect the directional qualities of the refractor.

What I claim as my invention is:

1. In a device of the class described, a 80 housing having openings therein, guides formed on the inside walls of the housing and cooperating with the openings to form an entrance and an exit, a pulley mounted in the housing, a flexible member trained 85 thereover, a fixture carrying member secured to one end of the flexible member, an annular enlargement on the fixture carrying member adapted to, when drawn up by the flexible member, engage the guides, and 90 a lateral projection on the fixture carrying member for aligning the fixture in a predetermined relation with the housing. 95

2. In a device of the class described, the combination with a lighting fixture having 95 directional qualities, of a suspension member, a guide mounted therein, a flexible member trained about the guide, a fixture carrying member non-rotatably fixed to the fixture and suspended by the flexible member, an extension on the fixture carrying member with which the flexible member is connected, a globular enlargement on the extension and adapted to engage the suspension member to support the fixture therefrom, and a lateral extension on the extension and having a thickness equal to the diameter of the extension, whereby rotation of the fixture with respect to the suspension member is restrained. 100 105 110

In testimony whereof I affix my signature.
ALWIN G. STEINMAYER.
